US0D1012114S

(12) **United States Design Patent** (10) Patent No.: **US D1,012,114 S**
(45) Date of Patent: ** Jan. 23, 2024

(54) **DISPLAY SCREEN OR PORTION THEREOF
WITH GRAPHICAL USER INTERFACE**

(71) Applicant: **Samsung Electronics Co., Ltd.**,
Gyeonggi-do (KR)

(72) Inventors: **Abhijit Z. Bendale**, Campbell, CA
(US); **Pranav K. Mistry**, Saratoga, CA
(US); **Bola Yoo**, Seoul (KR); **Kijeong
Kwon**, Seoul (KR); **Anil
Unnikrishnan**, Los Gatos, CA (US)

(73) Assignee: **SAMSUNG ELECTRONICS CO.,
LTD.**, Gyeonggi-Do (KR)

(**) Term: **15 Years**

(21) Appl. No.: **29/875,810**

(22) Filed: **May 10, 2023**

Related U.S. Application Data

(63) Continuation of application No. 29/850,771, filed on Aug. 23, 2022, now Pat. No. Des. 989,800, which is a continuation of application No. 29/765,738, filed on Jan. 11, 2021, now Pat. No. Des. 965,004.

CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee. The FIGURE is a front view of a display screen or portion thereof with graphical user interface, showing our new design.
